ART OF GRINDING

George D. Schoger, Anderson, Ind.

Application July 20, 1943, Serial No. 495,485

10 Claims. (Cl. 125—11)

This invention relates to the art of grinding, and pertains particularly to the maintenance of the grinding wheel by sharpening, truing and/or dressing the working face or faces of the wheel when needed, the specific form of the invention being in the nature of a dressing tool unit which is efficient in dressing activities and which can be bodily removed to permit the normal grinding activities and repositionable without the need of special adjustments for regrinding action.

The invention is designed more particularly for use in connection with grinders in which the work is carried on a bed capable of reciprocation and which is provided with suitable head stock and tail stock formations the centers of which serve to fixedly position the work relative to the grinding face. Machines of this type are in commercial service, and it is apparent that as a result of such service the grinding face or faces require dressing at intervals in the form of sharpening or truing the grinding faces by the use of a tool or implement which includes a dressing agency—generally a diamond—which is caused to traverse the curved face of the grinding wheel as the latter is rotated. The tool is positioned at the most efficient angle for service, and must be fixedly held in its adjusted position during the truing operation while traversing the face of the wheel through the movement of the bed. Where it is necessary to adjust the tool each time it is being placed in position, the operation becomes time-consuming since the specific adjustment made initially must be repeated each time the tool is being repositioned for dressing service, each truing operation thus representing a time expenditure of considerable extent and value where dressing is made frequently.

The present invention is designed to meet this condition by providing a unit which, after it has been once properly adjusted to provide the dressing operation, can be removed bodily as a unit and replaced as needed; since the adjustments are retained while the unit is inactive, it becomes necessary only to replace the unit in its position for service, and then provide the dressing operation. The unit is also additionally serviceable for dressing the sides of the grinding wheel, thus enabling the wheel dressing to include sharpening. The unit is of simple formation, sturdy in construction, simple as to adjustments, and of durability structurally.

To these and other ends, the nature of which will be readily understood as the invention is hereinafter disclosed, said invention consists in

the improved construction and combinations of parts hereinafter described in detail, illustrated in the accompanying drawing, and more particularly pointed out in the appended claims.

In the accompanying drawing, in which similar reference characters indicate similar parts in each of the views—

Figure 1 is a top plan view of the unit of the invention, certain parts of the grinding machine being shown by dotted lines, thus indicating the position of the unit during service.

Figure 2 is a side elevation of the unit, with parts broken away, the view also showing machine parts in dotted lines.

Figure 3 is a view, partly in section and partly in elevation of one form of supporting structure which may be utilized, this supporting structure serving as a part of the unit.

The grinding machine to be serviced is not disclosed in complete detail herein, but parts thereof are shown by dotted lines. For instance, the grinding wheel is shown at A, with a part of the bed shown at B, the latter being reciprocable across the face of the wheel, as indicated by the dove-tail guide b in Figure 2. The bed carries a head stock and a tail stock—the centering points of these are indicated respectively at C and D—these, during normal grinding operations, supporting the work being ground and which is moved across the face of the grinding wheel by reciprocating bed movements while the wheel is being rotated. There are a number of forms of machines of this type, but all of them utilize the above elements as a part of the equipment so that it is unnecessary to illustrate more than as indicated, these parts having direct relation to the unit operations.

The underlying fundamental of the present invention is presented by the fact that the unit is so formed and arranged that it can be substituted for the work in the work mounting, and by preventing unit rotation while permitting all necessary adjustments, it is possible to properly adjust the dressing tool relative to the wheel, after which the unit can be removed from and replaced in position with the ease and simplicity of a removal and positioning of a succession of the work pieces, the unit adjustments remaining constant so that the replacement restores the conditions as to angularity, etc., which were provided during the initial dressing action, ensuring uniformity in successive dressings.

Specifically, the unit or instrumentality is constructed of a number of members adapted to be assembled and adjusted relative to each other

and to the machine. The main members are the carrier 10 for the dressing tool, an L-shaped element 11 and a supporting member 12. Member 12 may be an elongated bar of uniform diameter having its ends recessed to cooperate with the head and tail stock centering devices; however, it is preferred that this member be of the adjustable type, provided by two elongated elements 12a of medium length, each element being provided with the recessed end 12b to cooperate with the centering pin, and the other end formed with an axial recess 12c which is threaded, the threads being formed to receive a threaded connection 12d to permit adjustment in the length of the member; obviously, on the initial positioning of the unit, either end element 12a of the assembly may be rotated to produce a desired length of member for use with the particular head and tail stock structures of the machine for which the unit is being prepared to provide the dressing operations. Member 12 is mounted in position on the head and tail stocks, after which carrier 10 and element 11 are clamped to it, these structures being provided with opposing notched faces to engage member 12 and position the unit.

The dressing tool carrier 10 is in the form of a block, preferably trapezoidal in form in side elevation and with the top and bottom preferably presenting the parallel sides, and with the bottom side of greater length from front to rear; this lower side carries the V-shaped notch 10a close to its front edge, this notch being designed to overlie the top of member 12. The block 10 carries a pair of inclined openings with the openings inclined downwardly from rear to front, the inclination being at a selected angle. These openings are arranged in spaced relation, with the axis of both openings lying on a plane angular to the top and bottom planes of the block. One of these openings 13, is designed to receive the dressing tool for the circular face of the grinding wheel, the opening being internally threaded, while the tool 14 therefor is of extended length and threaded externally, the tool having at its rear end a knurled head 14a by means of which the tool can be readily adjusted lengthwise of opening 13. The forward end of the tool is of the usual type, having a recessed threaded zone designed to receive the diamond-holding cup 14b, the diamond of which is to provide the dressing of the wheel face. The threaded zone of the tool carries a lock nut 14c cooperating with the rear face of the block to retain the tool in fixed position during the dressing operation.

The second opening, indicated at 15, extends parallel with opening 13 and is also screw-threaded. The opening is designed to receive the dressing tool (not shown) used for dressing the side faces of the grinding wheel; tools for this purpose are well known and are of different types. The block carries a set screw 15a designed to cooperate with such tool to retain it in its fixed adjusted position. Since the dressing of the sides of the wheel is only an occasional possibility, the unit is designed more particularly for the dressing of the peripheral face, but is formed to permit of the side face dressing if the latter is required.

Element 11 is a structure of general L-shape, being of a flat plate-like form one end zone of which is enlarged laterally to the width of block 10, being narrowed in rear of that zone and bent downwardly at a suitable point, the latter being determined generally by the approximate distance between the axis of member 12 to the rear

face of bed B. The upper face of element 11 is provided with a V-notch 11a in its forward zone, complementally positioned relative to notch 10a, the walls of the two notches permitting the block 10 and element 11 to be located in contact with the positioned member 12 carried by the head and tail stock structures, the contact becoming a clamping contact by the use of adjusting bolts 16, positioned at opposite sides of the assembly, and adjusting bolt or bolts 17—the latter may be single (located midway of the width of the assembly) or double (located at the sides), the latter arrangement being indicated.

Bolts 16 have their stems threaded and extend through openings in element 11—but without a threaded engagement with such element—and are threaded into a threaded opening 10b formed in the block. Bolts 17 are located rearwardly of bolts 16, and have their stems threaded and designed to pass through and threadedly engage the threaded walls of openings formed in element 11, with the free ends of the stems designed to engage the under surface of block 10. The two sets of bolts thus serve to clamp the block 10 and element 11 to member 12 and at the same time fixedly anchor the lower face of the block and the upper face of element 11 in spaced relation, with bolts 16 tending to draw the two together but only as permitted by the positions of the free ends of bolts 17.

The downwardly-extending leg 11b of member 11 is designed to overlie the rear of bed B and especially the dove-tail portion thereof. Normally, the head and tail stocks carried by the bed extend upwardly to a position where the work—carried by the head and tail stock center—is properly located as to height relative to the grinding wheel; this places the centers as materially above the top plane of the bed, the distance being dependent upon the particular machine and the position of the grinding wheel axis. Hence, when locating member 12 in the position of the work, the horizontal leg of element 11 generally extends rearwardly above the plane of the top of the bed. In practice the work axis generally lies on a horizontal plane extending through the grinding wheel axis, and hence, the substituted member 12 will cause the upper face of the horizontal leg of element 11 as slightly below such axial plane; since the axis of the dressing tool is located above such axial plane, it is apparent that the pressures developed during dressing, especially those caused by the rotation of the grinding wheel, will tend to rock the unit on the axis of member 12 (the ends of which are carried by the head and tail stock centers). To prevent this rocking movement, the leg 11b of element 11 preferably carries a pair of bolts 18 and 19, the former being positioned above and juxtaposed to the top of the bed—preventing material downward swing of element 11 under such pressures—while bolt 19 is positioned to extend below the lower edge of the dove-tail of the bed, preventing material rocking of member 11 upwardly—with the free end of the bolt contacting the bed below such dove-tail, the bolt carrying a lock-nut 19a for retaining the bolt in the adjusted position; since bolt 19, due to its contact with the rear of the bed can also serve to prevent rocking of the unit downwardly, it is apparent that the unit will be protected against such rocking movement even though bolt 18 be omitted—such omission is considered within the purview of the invention; however, it is preferred to also employ bolt 18 since it can serve to sup-

port the lengthy horizontal arm of element 11. Since grinding machines of this type vary in dimensions and in positions of various of the operating parts, the downwardly extending leg 11b is preferably provided with a plurality of the threaded openings 11c for bolts 18 and 19, thus enabling the latter to be secured in desired positions with different machines.

In providing the initial adjustments, the unit is accurately adjusted to the particular machine, after which the dressing tool is advanced to the desired point to provide the dressing action on the peripheral face of the grinding wheel, and the bed advanced to carry the tool across the face of the wheel—if the wheel is movable in the direction of its axis, the bed remains stationary; if the dressing requirements call for more than one pass of the tool, the latter is advanced for each additional pass, nut 14c being manipulated each time. After the last pass has been made, the unit is bodily removed from the machine by manipulating the head and tail stocks to remove the centers from the ends of member 12, thus completely freeing the unit from any positive connection with the machine. The unit is then placed aside in such condition, ready for repositioning when the succeeding dressing is required, at which time it is brought to the machine, the ends of member 12 aligned with the head and tail stock centers and the latter brought into position. It is then necessary only to adjust the tool to take care of any material decrease in dimensions of the grinding wheel, and the dressing operation made active; obviously, this permits the successive dressings to take place under similar conditions as to dressing tool angularity, etc.

As will be understood, the bolts 18 and 19—or bolt 19, if used alone—need not have a completely accurate location relative to the edges of the dove-tail; since the length of the horizontal leg of element 11 is many times that of the distance between the axis of member 12 and a vertical plane through the face of the dressing stone, it is apparent that material swinging of the dressing stone about the axis of member 12 can take place only by an extensive swing of the leg 11b in an arc about such axis, so that the simple looseness between the screw 19 and the lower edge of the dove-tail may be present without providing any material swing of the dressing stone. Hence, the dressing operation is had under practically steady conditions, although the unit itself is so arranged as to permit its bodily removal without disturbing any of the unit adjustments—removal and repositioning is provided with the simplicity of the removal of work from and the position of work relative to the grinding wheel.

While the above description presents the invention as applied to grinding machines wherein the work is moved relative to the grinding face in the direction of work axis, with the position of the grinding wheel remaining substantially constant, it is obvious that the invention is equally applicable for use with machines in which the grinding wheel is movable relative to the work additionally to the rotation of the wheel; for instance, the wheel support may be adjustable transverse of the bed—the wheel, rather than the work being the movable element in bringing the work and wheel face into active relation; or, the work may remain stationary in position, and the transverse and longitudinal movements may be by the grinding wheel. These present various

types of the grinding wheel structures in commercial use in addition to the form above discussed.

It is obvious, of course, that the invention is applicable for use with each of the types, since member 12 takes the position of the work in such machines, and the tool is supported by such member. Hence, whether the bed is movable toward the wheel face, or vice versa, or the wheel is shiftable axially rather than or additionally to the bed, there is relative movement between the bed, or the work thereon, and the grinding face, with the movement provided by one or both of these parts, depending upon the particular form of the machine. Since the tool is being substituted for the work in such machines, it is apparent that the tool can be utilized with each of the different types and be operative in accord with the normal practice of the machine or by such modifications therein as may be found desirable.

As is apparent, the unit, structurally, is of simple formation, sturdy, efficient in operation, and carries the advantage above pointed out. And while I have shown a preferred arrangement of the unit, it will be readily understood that changes or modifications therein may be found desirable or essential in meeting the exigencies of use or the individual desires of the user, and I therefore reserve the right to make any and all such changes or modifications as may be found necessary or essential insofar as the same may fall within the spirit and scope of the invention as expressed in the accompanying claims, when broadly construed.

I claim:

1. In means for dressing grinding wheels, wherein the grinding machine is of the type in which the work is carried by a bed with the work carried by head and tail stock centers and with the machine operative to provide relative movement between the work and grinding wheel in a direction parallel to the axis of the grinding wheel, said dressing means comprising a unit or instrumentality formed to support the dressing tool, said unit or instrumentality including a member cooperative with the head and tail stock centers, a dressing tool support and an L-shaped element clamped to the member to thereby definitely locate the unit relative to the grinding wheel peripheral face, said L-shaped element having one of its legs overlying the top plane of the bed and the other leg extending downwardly into overlying relation to the rear face of the bed, said latter leg carrying an adjusting screw adapted to underlie the dove-tail of the bed and to contact the body of the bed below the dove-tail, whereby the unit will be held against rotative movement on the axis provided by the mounting of the member on the head and tail stock centers, and whereby the unit is freely removable bodily by release of the member from the head and tail stock centers to thereby retain the initial adjustments of the unit and render the unit available for a succeeding dressing operation on the wheel by restoring the member to its position relative to the head and tail stock centers.

2. A unit as in claim 1 characterized in that the member is adjustable as to length.

3. A unit as in claim 1 characterized in that the member is formed of a pair of elements each having an end recess cooperative with a stock center and a threaded axial recess leading in-

wardly from its opposite end, the pair of elements being operatively connected in axial alignment by an interposed threaded element to permit adjustment in the length of the member.

4. A unit as in claim 1 characterized in that the dressing tool support is in the form of a block of trapezoidal form in side elevation, with the block having a threaded bore through which the dressing tool extends and is adjustably mounted, said bore having its axis inclined downwardly from rear to front of the block to thereby present the tool to the wheel peripheral face in direction approximating a radius of the wheel.

5. A unit as in claim 1 characterized in that the dressing tool support is in the form of a block of trapezoidal form in side elevation, with the block having a threaded bore through which the dressing tool extends and is adjustably mounted, said bore having its axis inclined downwardly from rear to front of the block to thereby present the tool to the wheel peripheral face in direction approximating a radius of the wheel, the angle of inclination of the bore being approximately normal to the angularity of the rear face of the block to the vertical to thereby permit the lock-nut of the dressing tool to lock the latter in its adjusted position.

6. A unit as in claim 1 characterized in that the dressing tool support is in the form of a block of trapezoidal form in side elevation, with the block having a threaded bore through which the dressing tool extends and is adjustably mounted, said bore having its axis inclined downwardly from rear to front of the block to thereby present the tool to the wheel peripheral face in direction approximating a radius of the wheel, said block carrying a second threaded bore positioned to permit mounting of a dressing tool for dressing the sides of the wheel.

7. A unit as in claim 1 characterized in that the dressing tool support is in the form of a block of trapezoidal form in side elevation, with the block having a threaded bore through which the dressing tool extends and is adjustably mounted, said bore having its axis inclined downwardly

45

from rear to front of the block to thereby present the tool to the wheel peripheral face in direction approximating a radius of the wheel, the forward zones of the lower face of the block end of the upper face of the L-shaped element being notched to receive the periphery of the center-supported member for the clamping operation.

8. A unit as in claim 1 characterized in that the dressing tool support is in the form of a block of trapezoidal form in side elevation, with the block having a threaded bore through which the dressing tool extends and is adjustably mounted, said bore having its axis inclined downwardly from rear to front of the block to thereby present the tool to the wheel peripheral face in direction approximating a radius of the wheel, the forward zones of the lower face of the block and of the upper face of the L-shaped element being notched to receive the periphery of the center-supported member for the clamping operation, the block and element assembly including a screw for directly connecting them in the clamped position and a screw for adjustably limiting the movements of the block toward the element.

9. A unit as in claim 1 characterized in that the downwardly-extending leg of the element additionally carries an adjusting screw adapted to overlie the top of the bed in the zone of the dove-tail, said screw together with the first screw presenting abutments cooperative with the dovetail for preventing rotative movements of the unit about the axis of the member.

10. A unit as in claim 1 characterized in that the downwardly-extending leg of the element additionally carries an adjusting screw adapted to overlie the top of the bed in the zone of the dove-tail, said screw together with the first screw presenting abutments cooperative with the dovetail for preventing rotative movements of the unit about the axis of the member, said leg being provided with a plurality of spaced openings to permit varied positioning of the adjusting screws to compensate for machine characteristics.

GEORGE D. SCHOGER.
